APPARATUS FOR FORMING ENCHAINED STITCHING LOOPS

Karl Maier, Stuttgart, Germany, assignor to
Union Special Maschinenfabrik, G. m. b. H.,
Stuttgart, Germany

Application May 21, 1927, Serial No. 193,272, and
in Germany June 5, 1928

4 Claims. (Cl. 112—199)

This invention relates to new and useful apparatus for forming chained stitching loops, the object being to provide an apparatus for forming chained stitching loops wherein the loops 5 to be chained are completely formed and subsequently interlocked one with another without the aid of the element forming the loops, or any element moving the material.

In the drawings which show by way of illustration one embodiment of the invention—

Figure 1 is a view partly in section showing a portion of a sewing machine embodying my improvements;

Fig. 2 is a view partly in section showing the cloth plate and the stitching elements with the needle at the lower end of its stroke;

Fig. 3 is a similar view, but showing the needle on its upward movement, and showing the previously formed thread loop as transferred from the retainer to the implement which removes the loop from the retainer and places it about the last-named thread loop;

Fig. 4 is a view similar to Fig. 3, but showing the previously formed thread loop as completely removed from the retainer;

Fig. 5 is a view similar to Fig. 4, but showing the implement which removes the thread loop from the retainer as having released the thread loop;

Fig. 6 is a plan view of the elements beneath the cloth plate positioned as shown in Fig. 3, the position of the needle also being shown in this Figure;

Fig. 7 is a sectional view on the line A, B of Fig. 3;

Fig. 8 is a view of the cloth plate and stitching elements positioned as in Fig. 1, but showing a modified form of retainer support, and

Fig. 9 is a view similar to Fig. 8, but showing also a modified form of the element for removing the thread loop from the retainer.

The machine herein described is designed for the purpose of forming thread loops in succession one after another and passing the same through a fabric, or beneath the plane of the fabric for interlocking, and interlocking a previously formed thread loop by a newly formed thread loop after the thread loops are completed, and without the aid of the implement which forms the thread loops, or any means for moving the fabric in any particular direction.

In the preferred form of the invention, the stitch forming elements include a needle which is eye-pointed and provided with a thread. This needle is reciprocated in a vertical line and passes

through an opening in the work support on which the fabric to be stitched is placed. Cooperating with the needle beneath the work support is a thread retainer having a hook-shaped end, and a recess in its under face. This hook-shaped 60 retainer is in the form of a looper and is adapted to enter the loop formed by the needle as it starts on its upward movement and retains the needle thread loop. The needle then moves to the upper end of its stroke, and on the next stroke forms 65 another loop, all the while the previously formed loop being held by the retainer. Before the retainer enters into the next loop thrown out by the needle, the element for removing the previously formed loop from the retainer moves into 70 the recess in the retainer and presents its hooked end through the previously formed loop and then moves downwardly so that said element on its backward movement may remove said previously 75 formed loop from the retainer, carrying the same over the hooked end thereof. Before it is removed, however, the retainer enters the next formed needle loop and engages the same for retaining it. The needle moves to the upper end of its stroke. Thus, there are two completely 80 formed thread loops beneath the fabric, both of which are around the retainer, and the needle point is above the material. The element which entered the previously formed loop withdraws the 85 loop from the retainer and places it about the shank of the last-formed needle thread loop.

Inasmuch as the thread loops are interlocked by the cooperative action of the elements beneath the cloth plate, the needle plays no part in the interlocking of the thread loops, except, of course, 90 that it holds the thread and draws on the thread in the setting of the stitches. Neither does the shifting of the fabric play any part in the placing of one thread loop on the other, and therefore, my improved method and apparatus is particularly adapted for forming chained stitching loops which may be used for darning; that is, closing holes in bags and other types of articles, 95 wherein it is essential that the article be moved in any desired direction for filling the hole with 100 the connected chained loops.

Referring more in detail to the drawings, I have shown a portion only of the work support or cloth plate 1 which is provided with a throat plate 2 having a needle opening 3 therethrough. The 105 needle 4 passes through this opening in the throat plate. The needle is provided with a thread 5. The chained thread loops are indicated at 6. These are of the usual character in a single thread chain stitch, and consist of indi- 110

vidual loops a^1 , a^2 , a^3 , of which the loops a^1 and a^2 may be said to be completed stitches; that is, they are enchainied one with another and the loops drawn down to form the finished stitches. 5 The loop a^3 is still held by the looper or retainer 7. This retainer is journaled at 8 and is oscillated on its support by means of a link 9. The link 9 is reciprocated in the usual manner, and it is not thought necessary to show in detail the 10 mechanism for accomplishing this reciprocation of the link 9.

Cooperating with the looper or retainer 7 is a second loop carrying element 11 which might also be referred to as a looper. This thread carrying 15 element 11 is pivoted at 10 to a lever support 14 which is journaled intermediate its ends at 13. This lever support is provided with a ball stud 15 which is connected to an eccentric strap 17 co-operating with an eccentric on the shaft 16. As 20 the shaft 16 rotates, it will rock the lever 14, and this will raise and lower bodily the thread carrier 11. The thread carrier 11 is oscillated on its pivotal support 10 by a link 12, which is reciprocated by any suitable means. The looper or 25 retainer 7 is provided with a recess 18 in its under face which extends from the extreme front end thereof well back along the shank of the retainer. The looper or retainer 7 is also provided with a downwardly extending projection 19 forming a hook for retaining the thread loop on the retainer. The thread carrier 11 is provided with a notch 20 forming a finger 21 which is adapted to enter the thread loop for removing the same 30 from the looper or retainer 7.

35 Starting with the parts positioned as shown in Fig. 1, there is a previously formed thread loop on the looper or retainer 7, and the needle is well down toward the lower end of its stroke. As the needle rises, a thread loop will be thrown 40 out, of the usual character, and the looper or retainer 7 enters this thread loop. Prior to the looper or retainer 7 entering the newly formed thread loop, the thread carrier 11 moves forward, and at a proper elevation, so that the finger 21 45 will enter the thread loop a^3 . This finger enters the recess 18, and therefore, the loop a^3 which encircles the looper is held open for the finger to enter, and the finger will positively enter said loop a^3 , placing the bite of the loop in the notch 50 20 of the thread carrying element 11. While the loop retainer 7 is still forward, the thread carrying element 11 moves downward, and this will position the thread loop a^3 so that it may be 55 readily removed from the looper or retainer 7 and carried over the hooked end 19 on said retainer. Meanwhile, the needle has proceeded on its upward movement, and there are two thread loops a^3 and a^4 about the retainer 7. The needle point is 60 well above the material, and while the needle point is above the material, the loop retainer and the loop carrying element move to the positions shown first in Fig. 4, and then in Fig. 5. As the thread carrying element moves to the position 65 shown in Fig. 4, it will strip or remove the thread loop a^3 entirely from the retainer, placing it about the shank of the loop a^4 , and then it releases said loop and the loop can be drawn up to form the 70 stitch.

75 Instead of describing the loop a^3 as removed from the looper or retainer 7, it may well be said that the thread carrying implement 11 holds the loop a^3 and the looper or retainer takes the new thread loop a^4 from the needle and draws it through the thread loop a^3 . The essential thing

is that the thread loop a^3 shall be secured or locked by the newly formed thread loop a^4 .

It is noted that this removing of the previously formed loop from the loop retainer and placing it around the shank of the newly formed loop, occurs while the needle is up, and the needle, in no way, cooperates with the interchaining of the thread loops, except, of course, that it holds the thread. Furthermore, inasmuch as the thread loops are interchainied positively by the cooperation of the elements 7 and 11 beneath the cloth plate, the direction of movement of the fabric plays no part in the enchaining of the thread loops. The fabric may be moved forward, backward, to the right or to the left, and in fact, in any direction, and it does not in any way interfere with the enchaining of the thread loops. Thus it is that the stitching mechanism which I have provided is of great advantage in darning holes in fabrics, or in performing any other character of work where it is desired to feed the material manually and control the direction of movement of the fabric at will.

In Figures 8 and 9, I have shown a slightly modified form of means for manipulating the retainer. In Figures 1 to 5, the retainer oscillates in a fixed path back and forth, while in Figures 8 and 9, the retainer moves in a straight line back and forth. Said retainer is carried by the support which reciprocates in a supporting lug carried by the cloth plate or frame of the machine. In Fig. 9, I have shown a similar form of support for the retainer, and a modified form of support for the thread carrying element. The body portion of the thread carrying element is substantially horizontal, and it may be moved by a suitable mechanism horizontally and vertically for carrying out the movements given to the thread carrying element 11, as shown in Fig. 1.

It is obvious that minor changes in the details of construction and the arrangement of the parts may be made without departing from the spirit of the invention as set forth in the appended claims.

Having thus described the invention, what I claim as new and desire to secure by Letters Patent, is—

1. A stitch forming mechanism including a work support, a needle for forming needle thread loops and passing the same through the work support, a looper having a hook-shaped end for entering the needle thread loop and retaining the same, a loop carrying implement having a hook-shaped end adapted to engage the thread loop carried by the looper and hold the same while the looper enters the next formed needle thread loop and carries the same through the previously formed loop held by the loop carrying implement.

2. A stitch forming mechanism including a work support, a needle for forming needle thread loops and passing the same through the work support, a looper having a hook-shaped end for entering the needle thread loop and retaining the same, a loop carrying implement having hook-shaped end adapted to engage the thread loop carried by the looper and hold the same while the looper enters the next formed needle thread loop and carries the same through the previously formed loop held by the loop carrying implement, said looper having a recess in its under face into which the hooked end of the loop carrying implement is adapted to move for engaging the thread loop on the looper.

3. A stitch forming mechanism including a work support, a needle for forming thread loops and passing the same through the work support, a

looper, actuating means for causing said looper to enter the needle thread loop and retain the same while the needle is forming its next thread loop, a loop carrying implement cooperating with 5 said looper and the actuating means for causing said loopcarrying implement to engage the needle thread loop on the looper and retain the same while said looper enters the next formed needle thread loop and retains said needle thread loop 10 while the first-named needle thread loop on the looper is passed off from the looper and about the shank of the last-named needle thread loop.

4. A stitch forming mechanism including a work support, a needle for forming thread loops

15

and passing the same through the work support, a looper, means for oscillating said looper to cause the same to enter a needle thread loop and retain the same, a second looper and means for oscillating said second looper and for raising and lowering the same, whereby said second looper is caused to engage the needle thread loop on the first looper and retain the same while the first looper enters the next formed needle thread loop and is retracted from said first formed needle thread loop carrying said second needle thread loop through the first formed needle thread loop.
